ORSON W. BRENIZER, OF PHILADELPHIA, PENNSYLVANIA, ASSIGNOR OF THREE-EIGHTHES TO ANDREW V. GROUPE, OF PHILADELPHIA, PENNSYLVANIA

CABLE SUPPORT

Application filed February 24, 1931. Serial No. 517,653.

This invention relates to improvements in cable supports or hangers adapted to be connected at intervals to a supporting or messenger wire and to receive and support a cable, the supporting or messenger wire being formed of a multiplicity of wire strands twisted around a central or core strand.

The twisted strands of the supporting or messenger wire provides it with relatively large and small diameters in alternate succession, which provide expanded portions at the large diameters and contracted portions at the small diameters, in alternate succession, on lines which extend parallel to the longitudinal axis of the supporting wire.

Cable supports have been constructed to cooperate with the shoulders formed by the expanded portions of the supporting or messenger wire to prevent displacement of the cable support longitudinally of the supporting wire when a cable is drawn through the support, and, at times, difficulty has been experienced in keeping all the cable supports in their proper places on the supporting wire due to irregularities in the parts of the cable support on the supporting wire or both or unusual strains or other causes while the cable to be supported by the cable supports is being drawn therethrough.

My present invention aims to overcome the aforesaid difficulty to a large extent and to lessen the danger of dislodging the cable supports from their proper positions on the supporting or messenger wire during the cable drawing operation, and I accomplish my object by the provision of a cable support of novel construction which will more effectively grip and co-operate with the supporting wire for the prevention of its displacement thereon than heretofore.

The invention resides in the novel construction, combination and arrangement of parts hereinafter described and claimed.

In the accompanying drawing illustrating the invention,

Figure 1 is a transverse section through a supporting or messenger wire showing my improved cable support applied thereto.

Figure 2 is a side view of the parts shown in Fig. 1.

Figure 3 is a top view of the parts shown in Fig. 1.

Figure 4 is a view of the cable support in the normal condition thereof before being applied to a supporting wire.

Figure 5 is a transverse section through the supporting wire, on line 5—5 of Fig. 2, showing one of the hooks of the cable support applied thereto.

Figure 6 is a transverse section through the supporting wire, on line 6—6 of Fig. 2, showing parts of the cable support applied thereto.

Referring to the drawing, 2 designates the supporting or messenger wire and 3 the cable support thereon.

The supporting wire 2 comprises a central or core strand and outer strands lying side by side in close relationship and twisted in spiral or helical form around the core strand. The supporting wire 2 has relatively large diameters 7 and small diameters 4, in alternate succession which provide the supporting wire with expanded portions at the large diameters 7 and contracted portions at the small diameters 4, in alternate succession on lines which extend parallel to the axis of the supporting wire 2.

The cable support 3 is formed of a single piece of spring wire which is flat in cross section, and it comprises a cable receiving loop 8, obliquely extending arms 9 and 10 diverging upwardly from the respective sides of the loop 8, hooks 11 and 12 extending upwardly from the upper end portions of the arms 9 and 10, respectively, an arm 13 extending from the hook 11 and an arm 14 extending from and forming in effect, a continuation of the arm 13.

The hooks 11 and 12 are disposed opposite to each other and they embrace the supporting wire 2 from opposite sides thereof to connect the cable support thereto in a manner to permit it to serve as a support for suspending a cable, indicated at 27 in Fig. 1, from the supporting wire.

The loop 8 is formed by a flatwise bend in the wire forming it and it extends transversely of the supporting wire 2 for the reception of the cable 27, and the diverging arms 9 and

10 space the hooks 11 and 12 longitudinally of the supporting wire.

The hooks 11 and 12 are formed by flatwise bends in the wire forming them. They are provided with bottom parts 16 and 17 which extend under the supporting wire 2, and top parts 18 and 19 which extend over the supporting wire 2, respectively.

11 The arm 13 is joined to the top part 18 of the hook 11 by an abrupt edgewise bend 15 in the wire forming them, such edgewise bend being located over the supporting wire 2. The arm 13 extends from the top part 18 of the hook 11 downwardly and outwardly over 15 one side portion of the supporting wire 2 and in a direction away from the space between the hooks 11 and 12.

12 The arm 14 is joined to the arm 13 by an abrupt edgewise bend 20 in the wire forming them, and the arm 14 extends downwardly and inwardly from the arm 13 and under the side of the supporting wire 2 over which the arm 13 extends.

13 The arm 13 is provided with an elbow 21 formed therein by a flatwise bend in the wire forming the arm to cause the arm 13 and the lower portion of the arm 14 to occupy particular positions with relation to parts of the supporting wire 2 as and for a purpose presently explained.

14 The arms 13 and 14 are located on the same side of the supporting wire 2 and the curved portion of the hook 12 connecting the top portion 19 and bottom portion 17 thereof, and on the opposite side of the supporting wire 2 to the curved portion of the hook 11 connecting the top portion 18 and the bottom portion 16 thereof.

15 In applying the cable support 3 to the supporting or messenger wire 2, the cable support is turned and manipulated by hand to pass the arms 13 and 14 over the supporting wire 2 and down opposite to one side thereof in advance of applying the hook 11 to embrace the wire 2 from the opposite side thereof. After the arms 13 and 14 and hook 11 have been applied to the wire 2, the hook 11 fits the wire 2 sufficiently loose to allow it to rock enough to permit the hook 12 to be moved 20 under the wire 2 while the hook 11 is being applied thereto. During and after the application of the hook 11 to the wire 2, the hook 12 is moved beneath the wire 2 in the direction of the arrow 22 by springing the loop or body 8 of the support 3 until the free end of the hook 12 clears the side of the wire 2 on which the arrow 22 is located; whereupon the hook 12 is raised and placed in embracing engagement with the wire 2, as shown in the drawing, while the loop or body portion 8 of the support 3 is permitted to spring back toward its normal condition. When the hook 12 is thus applied to the wire 2, the loop 8 is sprung in opposition to pressure of the hook 11, in the direction of the arrow 23,

21 against the wire 2, and in opposition to pressure of the arms 13 and 14, in the direction of the arrow 24, against the wire 2.

22 Before the cable support 3 is applied to the supporting wire 2, the hooks 11 and 12 are spaced apart, laterally of the wire 2, as shown in Fig. 4, and the respective sides of the loop 8 are more widely separated, so that after the support has been applied to the wire 2, the tendency of the loop 8 to resume its normal condition, as shown in Fig. 4, will cause the hooks 11 and 12 to be pressed firmly against the wire 2 in the directions of the arrows 23 and 22, respectively, and will cause the arms 13 and 14 to be pressed firmly against the wire 2 in the direction of the arrow 24.

23 The sides of the arm 14 and that portion of the arm 13 below its elbow 21 which face the supporting wire 2 are substantially straight and set at such angles with relation to each other and to the wire 2 that when the cable support 3 is applied to the supporting wire 2, as shown in Figs. 1, 2 and 3, the arm 14 and the lower portion of the arm 13 will embrace one of the strands of the wire 2 and enter contracted portions of the wire 2 below and above the embraced strand, respectively, and thus occupy positions to encounter expanded portions of the supporting wire 2 and be thereby prevented from being 28 displaced longitudinally of the wire, when a cable is drawn through the cable support.

24 The relation of the arm 14 and the lower portion of the arm 13 to the supporting wire 2, as shown and described, is such that should a cable being drawn through the cable support in the direction of the arrow 25 in Fig. 2 tend to cant the support in that direction, such tendency will cause the arm 14 and the upper portion of the hook 11 to be forced into firmer engagement with the wire 2; and that should a cable being drawn through the support 3 in the direction of the arrow 26 in Fig. 2 tend to cant the support in that direction, such tendency will cause the lower portion of the arm 13 and the hook 11 to be forced into firmer engagement with the wire 2. As there is nearly always a tendency to cant the cable support while a cable is being drawn therethrough, the utilization of such tendency to effect a firmer grip of either or both of the arms 13 and 14 upon the supporting wire 2 is a factor of considerable importance in preventing displacement of the cable support 3 on the supporting wire 2, independently of the relation of the arms 13 and 14 to the expanded and contracted portions of the supporting wire 2.

25 Either the space between the parts 16 and 18 of the hook 11 or the space between the parts 17 and 19 of the hook 12 or both are preferably made less than the diameter of the expanded portions of the supporting wire 2, so that the hooks 11 and 12 may embrace contracted portions of the wire 2 and be pre-

vented by expanded portions thereof from being displaced longitudinally of the wire.

I claim:

1. A cable support adapted to be applied to a supporting wire formed of twisted strands providing sections of relatively varying diameters in alternate succession longitudinally of the wire, said support being formed of a piece of flat spring wire and comprising a cable receiving loop formed by a flatwise bend in the wire forming it, oppositely directed spaced hooks extending from the respective end portions of the loop and being formed by flatwise bends in the wire forming them and being adapted to embrace the supporting wire from opposite sides thereof, one of said hooks having a bottom part adapted to extend under the supporting wire and a top part adapted to extend above the bottom part and over the supporting wire, said top part and said bottom part being substantially in parallel relation and in a common plane extending transversely of the supporting wire normal to the axis thereof, and a downwardly and outwardly inclined arm connected to said top part by an angular edgewise bend in the wire forming them and adapted when the support is in use to extend therefrom from a position over the supporting wire to a position adjacent to one side thereof, said arm having a substantially straight edge portion adapted to face and have a biting engagement with one side of the supporting wire and to force the hook to which the arm is connected toward the opposite side of the supporting wire when the support is canted in a direction to lower said arm.

2. A cable support adapted to be applied to a supporting wire formed of twisted strands providing sections of relatively varying diameters in alternate succession longitudinally of the wire, said support being formed of a piece of flat spring wire and comprising a cable receiving loop formed by a flatwise bend in the wire forming it, oppositely directed spaced hooks extending from the respective end portions of the loop and being formed by flatwise bends in the wire forming them and being adapted to embrace the supporting wire from opposite sides thereof, one of said hooks having a bottom part adapted to extend under the supporting wire and a top part adapted to extend above the bottom part and over the supporting wire, an arm connected to said top part by an angular edgewise bend in the wire forming them and extending therefrom in a downward direction away from the space between said hooks, and an arm connected to the first named arm by an edgewise angular bend in the wire forming them and adapted to extend therefrom inwardly beneath the supporting wire and having one of its broad surfaces facing said bottom part and having

a substantially straight edge portion adapted to face and have a biting engagement with the supporting wire in an upward direction when the support is canted in a direction to raise the last named arm.

3. A cable support adapted to be applied to a supporting wire formed of twisted strands providing sections of relatively varying diameters in alternate succession longitudinally of the wire, said support being formed of a piece of flat spring wire and comprising a cable receiving loop formed by a flatwise bend in the wire forming it, oppositely directed spaced hooks extending from the respective end portions of the loop and being formed by flatwise bends in the wire forming them and being adapted to embrace the supporting wire from opposite sides thereof, one of said hooks having a bottom part adapted to extend under the supporting wire and a top part adapted to extend above the bottom part and over the supporting wire, a downwardly and outwardly inclined arm connected to said top part by an angular edgewise bend in the wire forming them and adapted when the support is in use to extend therefrom from a position over the supporting wire to a position adjacent to one side thereof, said arm having a substantially straight edge portion adapted to face and have a biting engagement with one side of the supporting wire and to force the hook to which the arm is connected toward the opposite side of the supporting wire when the support is canted in a direction to lower said arm, and an arm connected to the first named arm by an edgewise angular bend in the wire forming them and adapted to extend therefrom inwardly beneath the supporting wire and having one of its broad surfaces facing

said bottom part and having a substantially straight edge portion adapted to face and have a biting engagement with the supporting wire in an upward direction when the support is canted in a direction to raise the last named arm.

In testimony whereof I affix my signature.
ORSON W. BRENIZER.
